UNITED STATES PATENT OFFICE.

JAMES A. JOHNSON, OF CHARLESTOWN, INDIANA.

LAND-ROLLER.

SPECIFICATION forming part of Letters Patent No. 319,725, dated June 9, 1885.

Application filed November 25, 1884. (No model.)

To all whom it may concern:

Be it known that I, JAMES A. JOHNSON, of Charlestown, in the county of Clarke and State of Indiana, have invented certain new and useful Improvements in Land-Rollers; and I do hereby declare that the following is a full, clear, and exact description of the invention, which will enable others skilled in the art to which it appertains to make and use the same, reference being had to the accompanying drawings, which form a part of this specification, and in which—

Figure 1 is a top view of my improved land-roller. Fig. 2 is a transverse vertical sectional view of the same. Fig. 3 is a longitudinal vertical sectional view, and Fig. 4 is a detail perspective view.

The same letters refer to the same parts in all the figures.

My invention has relation to land-rollers, and contemplates certain improvements on the land-roller for which Letters Patent No. 288,061 were granted to me on the 6th day of November, 1883; and it consists in the improved construction and combination of parts of the same, as hereinafter more fully described and claimed.

In the drawings hereto annexed, A designates the frame of my improved land-roller, which is rectangular in shape, and provided at the front with a tongue, B, attached by means of braces C, or in any suitable manner. The said frame is provided with a central division-bar, D, the sides of which have conical bearing-studs E E, provided with cylindrical bearings for the ends of the axles F F, the outer ends of which are journaled in suitable bearings, G G, in the outer or side beams of the frame. Upon the revolving axles F F are journaled the rollers H H, the ends or heads of which are constructed of open-work castings I I, and the bodies of which consist of cylinders of wrought or cast iron, as shown at J J. The inner castings, I, have hubs K, provided with cylindrical extensions L, surrounding the conical bearing-studs E, and the hubs M of the outer castings are provided with set-screws N, by means of which they may be secured upon their respective axles. It will be seen that by this construction, while the rollers are capable of revolving upon their axles, they may also be fixed upon and caused to revolve with the said axles,

and when the recesses in the extensions L are worn the rollers may be drawn toward the 55 division-bar and be secured by means of the set-screws, causing the recesses in the extensions to fit upon the conical bearings, steady- ing the revolutions of the rollers.

This improved roller is weighted by means 60 of boxes or baskets Q Q, having arms R R, by means of which they are hung upon the axles within the rollers, and in which rocks or other weights may be placed. These swing- ing boxes or baskets will always gravitate to 65 the lowest point, where their influence will be most efficiently exercised.

From the foregoing description, taken in connection with the drawings hereto annexed, the operation and advantages of this invention will be readily understood. The construction is simple and inexpensive. The rollers are capable of lateral adjustment in the manner and for the purposes described, and they may be caused to revolve with or upon 75 the axles, as may be desired.

I am aware that it is not broadly new to have conical sleeves or thimbles around the ends of an axle or shaft fitting into conical recesses in the hub of a wheel or roller re- 80 volving upon the said axle or shaft, and I do not wish to claim such construction, broadly; but

I claim—

In a land-roller, the combination of a 85 frame, a division-bar having conical bearing- studs with cylindrical bearings for the inner ends of the axles, the side beams having boxes or bearings in their inner ends for the outer ends of the said axles, the axles journaled in 90 the bearings of the division-bar and the outer frame-beams, and the rollers, the inner heads or ends of which are provided with cylindri- cal collars engaging the conical bearings of the division-bar, and the outer ends of which 95 have set-screws for adjusting the rollers upon the axles, substantially as and for the purpose herein set forth.

In testimony that I claim the foregoing as my own I have hereunto affixed my signature 100 in presence of two witnesses.

JAMES A. JOHNSON.

Witnesses:

WILLIAM F. BOYER,
JOHN H. POOL.
